UNITED STATES PATENT OFFICE.

LOUIS H. SHOLDER, OF CLEVELAND, OHIO.

PRUNING-KNIFE.

SPECIFICATION forming part of Letters Patent No. 400,800, dated April 2, 1889.

Application filed September 10, 1888. Serial No. 285,059. (No model.)

To all whom it may concern:

Be it known that I, LOUIS H. SHOLDER, a citizen of the United States, residing at Cleveland, in the county of Cuyahoga and State of Ohio, have invented certain new and useful Improvements in Corn-Cutting Knives; and I do hereby declare that the following is a full, clear, and exact description of the invention, which will enable others skilled in the art to which it appertains to make and use the same.

My invention relates to improvements in corn-cutting knives; and it consists in a knife provided with a wire handle and constructed substantially as shown and described, and particularly pointed out in the claim.

In the accompanying drawings, Figure 1 is a plain side elevation of my improved knife. Fig. 2 is an edge view. Fig. 3 is a longitudinal section of the handle; and Fig. 4, a detail of one of the handle-blocks.

In the drawings, A represents the blade of the knife. This blade or cutter is cimeter-shaped in some particulars, but is purposely made with increasing width from the shank or handle to its outer extremity, and is much the heaviest at said outer extremity to give increased strength and weight at that point, where the strain on the cutter comes in work, and where weight materially contributes to the effectiveness in the blow for severing the stalks. Both edges *a* *b* of the blade are sharpened, the edge *a* being slightly convex in outline and the edge *b* concave in outline, and both terminating in a straight or square outer edge, *c*. It will be observed that the edge *b*, while it is concave in curvature, runs down rather abruptly from 2 to point 3. This is to enable the user to give somewhat of a drawing cut in the after part of the blow, which with some is regarded as a very material advantage in a knife of this kind, and those persons will not use a knife that does not possess this peculiar merit. Others again are prejudiced against this form of blade, and will use none that has not the convex edge, as shown at *a*. I have therefore conceived the idea of embodying the two principles of construction in a single blade, and thereby providing a knife which is adapted to the choice of either class of users. These knives,

of course, are made for many years' service, and they fall into many different hands before they are worn out. Again, some men will use the different edges alternately, claiming that as the stroke and action are different between the two edges they can spell and rest themselves more or less in this way; or if one edge should become dulled the other can be temporarily used until the preferred edge is sharpened. By sharpening both edges and shaping them as here shown I gain the advantage practically of combining two tools in one, and both demands for the two different kinds of cutters are supplied in the single cutter thus offered. This works material economy and advantage to the consumer, and enables the trade to carry a single line of goods to meet all demands for what would otherwise be two lines and wholly different articles.

Another improved feature of my cutter lies in the construction of the handle D. This handle, it will be seen, is essentially a wire handle, or a handle closely and firmly wrapped with wire, *d*. The outline of the shank of the handle, which is an extension of the blade material, is shown in Fig. 1, where it is seen to have a swell at the center *d'* and an enlargement at the end *d''*, adapting the shape to the needs of the hand for gripping and controlling the blade, and at the same time serving to prevent the wire from stripping off. Body is given to the handle along about its center, on either side of the shank, by means of blocks *e*, tapered from their middle toward both ends, and forming a support as well for the wire covering with which they are entwined. A handle thus made will stand any amount of the hardest usage without danger of injury. It cannot be split or broken or otherwise damaged, and the surface is just rough enough, by reason of the wire ribs, to form a good hold for the hand, while it is not so rough or uneven as to injure the hand.

Altogether a very greatly improved implement for cutting corn is produced by this construction, and advantages are combined which are not possessed by other devices or cutters in existence.

Having thus described my invention, what I

claim as new, and desire to secure by Letters Patent, is—

5 A cutter-blade having a handle provided with a piece at either side, which is highest at its center and inclines toward each extremity, whereby a swell is formed centrally in the handle, in combination with wire wrapping about the shank and piece to form

the covering of the handle, substantially as set forth.

In testimony whereof I hereunto set my hand this 3d day of September, A. D. 1888.

LOUIS H. SHOLDER.
